UNITED STATES PATENT OFFICE.

ARTHUR J. MASKREY, OF CANTON, OHIO.

ROLL-SCRAPER.

1,387,896.

Specification of Letters Patent. Patented Aug. 16, 1921.

Application filed November 9, 1918. Serial No. 261,777.

To all whom it may concern:

Be it known that I, ARTHUR J. MASKREY, a citizen of the United States, residing at Canton, in the county of Stark and State of Ohio, have invented a new and useful Roll-Scraper, of which the following is a specification.

This invention relates to roll scrapers, the object being to construct a roll scraper with substantially a chisel edge and of material of the proper hardness to retain the said chisel edge while in use.

Another object is to greatly cheapen the cost of manufacture of roll scrapers.

15 A further object is to construct a roll scraper that will far outlast roll scrapers of the type now known and employed, thereby effecting further economy in both expense, time and labor, since the roll scrapers which 20 I have devised will not need replacing with anywhere near the frequency of the present type.

With these objects in view the invention consists in the novel construction and arrangement of parts, hereinafter described, 25 illustrated in the accompanying drawings, and particularly pointed out in the appended claims, it being understood that various changes in the form, proportions, 30 size and minor details of construction may be made within the scope of the appended claims, without departing from the spirit or sacrificing any of the advantages of the invention.

35 In the drawings:

Figure 1 is a plan view of a tinning machine equipped with my roll scrapers, parts of the rolls being broken away to disclose the roll scraping devices.

40 Fig. 2 is a transverse sectional view on line 2—2, of Fig. 1.

Fig. 3 is an enlarged detailed section of a portion of a roll and a portion of one of the arms carrying a section of the scraper, shown 45 in position.

Fig. 4 is a similar view showing a modified form of scraper blade.

Fig. 5 is a still further enlargement showing the relation of the chisel edge to the 50 roll.

Similar numerals of reference indicate corresponding parts throughout the several figures of the drawings.

In the process of manufacture of tin plate, 55 a pot containing the molten tin, is employed, and through this pot are passed the un-

coated sheets, pairs of rolls being superposed above the outlet of the pot are designed to distribute evenly over the faces of the sheets the accumulation of molten tin, which adheres to the sheet while passing through the tin pot. A guide way is formed through the pot so that the sheets passed in at one end will be directed to a point to engage the first of the pairs of rolls. 60 To those familiar with the tin plating process it is well known that there is always present in the molten tin within the tin pot, a quantity of minutely granular particles of foreign matter. This foreign substance 65 is known as "scruff" and as the uncoated sheet is passed through the tin pot, a quantity of this "scruff" is accumulated on the face of the sheet along with the molten tin. As the sheet is passed upwardly and comes into 70 contact with the first of the pairs of rolls the pressure of the said rolls upon the opposite sides of the sheet will remove the surplus of molten tin, leaving the faces of the sheet coated and returning the surplus 75 tin to the tin pot. The "scruff" which was carried upwardly on the newly coated sheet will adhere to and be accumulated upon the surface of the rolls. Should any of this accumulation of "scruff" remain upon the 80 rolls as it rotates and be brought into contact with the face of the sheet, the said sheet would present an unsightly appearance, the newly plated surface of the sheet 85 appearing dull and imperfectly coated. In 90 order to remove this accumulation of "scruff" at each revolution of the rolls, a scraper is positioned to contact with the surface of the roll, so that a perfectly clean face of the roll will be presented to the sheet. 95 Passing upwardly from the first pair of rolls, the sheet encounters a second pair of rolls equipped with scrapers identical with the first pair, the operation being repeated substantially as on the lower rolls. 100 The rolls upon which the scrapers embodied in this invention are applied are contained in what is known as the grease pot only and they receive the sheet after it has passed upward through the tinning medium. These rolls are what are termed 105 finishing rolls and they rotate within grease, receiving the coated sheets, and this appliance removing the surplus molten tin and especially the scruff on the rolls, leaving the 110 faces of the sheets coated and returning the surplus tin and scruff to the tin pot.

Various types of roll scrapers have been and are now employed for removing this accumulation of "scruff" from the face of the rolls, but all of the now known devices employed for scraping the rolls have proven unsatisfactory for one reason or another. Various materials and types of scrapers have been discarded for the reason that they either will not hold up under the heat in which the scraper must work or that they will not present a clean scraping edge. The type of scraper found most satisfactory heretofore and the type which has been in general use for a number of years and is now generally used, is composed of asbestos and metal fabric, woven together. While the asbestos will stand up under the continued heat it will not long maintain a proper scraping edge to effectively remove all of the "scruff" from the surface of the rolls. A further objection is that when the asbestos has worn a trifle to allow the metal fabric to come to the surface, a series of metal points formed by the wires composing the fabric are presented to the face of the roll and constant rotation of the roll against these points of metal will eventually cause the roll to become roughened and rendered unfit for further use. Because of these objections this type of scraper must be renewed at very frequent intervals, in mills where a constant operation is maintained these changes being found necessary in about two to four weeks and since the materials employed in constructing the scrapers are of considerable expense, the constant renewal necessary produces an inconsistently high operating expense in the manufacture of the product. After several years of experience and experiment I have devised the herewith illustrated roll scraper which is shown applied to an ordinary tinning machine in which the tin pot designed to contain the molten tin is shown at 1. A guide 2 within the pot is designed to cause the plate passed through the molten metal to be guided into contact with the first pair of rolls shown at 4. These rolls, of course, will be rotated in the proper direction to pass a sheet brought between them from the bottom upwardly, whence the sheet is brought between the next pair of rolls shown at 5, which are also rotating to carry the sheet upwardly. A longitudinal beam 6 extends along either side of the machine at a point slightly above the top of the upper pair of rolls and to each of these beams is secured a plurality of downwardly extending arms 7, the said arms being preferably equi-distantly spaced, one from the other. The arms 7 are secured to the beam by means of bolts 8, which bolts also secure upon the upper side of the beams and in alinement with the arms 7 a plurality of inwardly

extending support plates 9. A pair of vertically disposed rods 10 extend through apertures formed adjacent the inner extremities of each of the plates 9, the said rods being threaded at their upper extremities to receive nuts 11. Washers 12 are held in place upon each of the rods 10 by means of the nuts 11 and interposed between each of the washers 12 and the upper face of each of the plates 9 is a coiled spring 14 which exerts an upward force upon the rod 10 through its contact with the washer upon the said rod. The lower end of each of the rods 10 is bifurcated and straddles an arm 15, which arms are pivoted to the arms 7. A pin is inserted through the bifurcated ends of the rods 10 and through the arms 15, thus forming substantially a pivotal connection between the said rods 10 and arms 15. The inner extremities 16 of the arms 15 are bent at right angles, the said bent ends being secured by means of bolts 17 to a pair of longitudinal binding strips 18 and 19, between which binding strips is secured one of the scraper blades shown at 20. These scraper blades are formed of hardened steel and are beveled as at 21 to form a chisel edge 22, which chisel edge is held against the face of the roll. The blades 20 will each be the full length of the rolls so that no joint is necessary.

By forming my scraper blades of hardened steel I am enabled to produce a blade which will not only stand up under the heat in which the scraper is used, but will also retain a sharp scraping edge. The hardened steel plate will always maintain an even and constant contact with the face of the roll and will not be easily nicked. Actual test has proven that one of my scraper blades will continue to withstand constant service for a period of about one year, which taken with the fact that the initial cost of one of my blades is less than one quarter of the cost of the now known and employed blades, which have to be replaced about bimonthly, it is apparent that enormous economy is effected.

In Fig. 4 I have shown a slightly modified form in which I substitute a plurality of steel plates shown at 25 for the blade 20, of the other figures. By using this construction, should the blade which sustains the wear against the roller become damaged in any manner, it can be removed and the next blade brought to bear against the roller.

It should be noted that the scraper blades are located radially with reference to the rolls preventing the cutting of the rolls by the scrapers while at the same time the springs provided in the scraper mechanism insure an even contact between the scraper and the face of the roll. It should be understood that in time the chisel edges of the scraper blades become worn away and

the edge of the scraper blade will become sufficiently worn to fit snugly against the periphery of the roll, but this does not destroy the efficiency of the device and the 5 scraper blades may be used until they are entirely worn away.

Having fully described my invention what I claim as new and desire to secure by Letters Patent, is—

- 10 1. In a tin coating device comprising a grease pot and superposed pairs of rolls therein, a pivoted arm adjacent to each roll, a radially disposed blade on each arm formed from a single rigid steel plate and
- 15 provided with a chisel edge arranged to contact evenly with the face of the roll and tension means common to the pivoted arms

upon each side for holding the chisel edges of the blades in contact with the rolls.

2. In a tin coating device comprising a 20 grease pot and superposed pairs of rolls therein, a pivoted arm adjacent to each roll, a radially disposed blade on each arm formed from a single rigid steel plate and provided with a chisel edge arranged to contact evenly with the face of the roll and a 25 spring pressed rod connected to each pivoted arm intermediate the ends thereof for holding the chisel edges of the blades in contact with the rolls.

In testimony that I claim the above, I have hereunto subscribed my name.

ARTHUR J. MASKREY.
